CLAIM

The ornamental design for an “articulating display mount”, substantially as shown and described.

DESCRIPTION

FIG. 1 is a first isometric view of an articulating display mount.

FIG. 2 is a front view of the articulating display mount of FIG. 1.

FIG. 3 is a rear view of the articulating display mount of FIG. 1.

FIG. 4 is a bottom view of the articulating display mount of FIG. 1.

FIG. 5 is a top view of the articulating display mount of FIG. 1.

FIG. 6 is a first side view of the articulating display mount of FIG. 1; and,

FIG. 7 is a second side view of the articulating display mount of FIG. 1.

The features shown in broken lines form no part of the claimed design.
